UNITED STATES PATENT OFFICE.

LEWIS T. WILCOX, OF PEEKSKILL, NEW YORK, ASSIGNEE TO WILCOX PATENTS CORPORATION, OF PEEKSKILL, NEW YORK, A CORPORATION OF NEW YORK.

OVEN.

Application filed May 16, 1925. Serial No. 39,668.

This invention relates to ovens, and particularly to the portable type which may be placed over open burners such as gas and liquid petroleum burners.

5 An object of the invention is to provide an improved oven, which may be made largely or practically entirely of sheet metal; which will be relatively strong, efficient, durable, and inexpensive; and in 10 which the various parts may be united by seams that may be formed largely by machines commonly used for that purpose in sheet metal working.

15 A further object is to provide an improved oven formed largely of sheet metal, in which the various parts may be easily and rapidly assembled into a strong, durable structure with a minimum of operations.

20 A further object is to provide an improved oven in which the hot gases entering the oven for heating purposes will be directed and conducted in such a manner as to provide a maximum uniformity of the 25 heat throughout the oven, including the side walls, and in which the door, when latched, will be drawn and held tightly closed.

30 A further object is to provide an improved grate for ovens which may be formed from standard stock rolled metal with a minimum of operations, and which will have maximum rigidity and strength and which will be light in weight, durable and relatively inexpensive.

35 Various other objects and advantages will be apparent from the following description of an embodiment of the invention, and the novel features will be particularly pointed out hereinafter in connection with the appended claims.

40 In the accompanying drawings:—

Fig. 1 is an end elevation of a portable oven constructed in accordance with the invention;

45 Fig. 2 is a longitudinal sectional elevation of the same, with the section taken substantially along the line 2—2 of Fig. 1;

50 Fig. 3 is a partial transverse sectional elevation of the same, with the section taken substantially along the line 3—3 of Fig. 2;

Fig. 4 is a sectional plan through a portion of the oven, illustrating the latch for the door;

55 Fig. 5 is a sectional elevation of a portion of the construction shown in Fig. 4, with

the section taken substantially along the line 5—5 of Fig. 4;

Fig. 6 is a sectional plan through a portion of the oven, illustrating the mounting of the hinge for the door, the section being 60 taken substantially along the line 6—6 of Fig. 1;

Fig. 7 is a perspective of an improved grate which may form part of the oven; and

Fig. 8 is a sectional elevation through a 65 portion of the grate and illustrating the manner of connecting the transverse bars to the channel.

In the illustrated embodiment of the invention, a tubular sheet metal outer shell 1 70 is closed at one end by an end wall 2, which has a seamed connection 3 thereto, the end wall having an internal shoulder 4 formed therein and extending substantially parallel to and spaced from the marginal edge of 75 the end wall for a purpose which will appear presently. An inner tubular sheet metal shell 5 is disposed within the outer shell, with its peripheral wall spaced from the outer shell. This inner shell is closed 80 at one end by an end wall 6 of sheet metal which is seamed thereon as at 7, the seam forming an endwise peripheral flange which fits within the limits of the shoulder 4 of the outer end wall, so as to support the inner 85 shell in spaced relation from the side wall of the outer shell, and the seam 7 which projects outwardly from the end wall 6 of the inner shell, and spaces apart the two abutting walls of the shells to create a small 90 insulating chamber 8.

An end frame 9 of sheet metal is fitted against the open ends of the inner and outer shells and seamed to the open end edges of said shells in a manner to close the space 95 between the two shells at the open ends, and at the same time not cover or close the open end of the inner shell. A door member 10 is secured by hinges 11 to the frame 9 at one side, in such a manner as to permit the 100 door to swing across and close the open end of the inner shell. This door 10 (see Figs. 4 and 6) comprises two sheet metal walls 12 and 13, the outer wall 13 being spaced from the inner wall 12 throughout the major portion of the door area, but being bent at the margins as at 14 to abut flat against the wall 12, the marginal edges of the two walls 12 and 13 being seamed together at their edges, as at 15, and bent hook-like so 110

as to overlie or hook over the seams between the frame 9 and the open end edge of the inner shell, as shown in Fig. 4.

At the side of the door opposite the hinges, the flattened portion 14 of the outer wall 13 is slightly enlarged in area, as at 15^a, to provide a surface upon which a suitable latch may be mounted. This latch comprises a base element 16 having a reduced pivot extension 17 passing through and rotatably mounted in the two walls 12 and 13, the inner end carrying a locking arm 18 which is held thereon by upsetting or riveting over the inner end of the extension 17. A handle bail 19, or other operating member, is hinged or otherwise secured to the base element 16 to enable rotation of the base element and the arm 18, the bail element 19 having a handle 20 of insulating material so that it may be operated while the oven is hot or in use.

The side wall of the inner shell 5 is provided adjacent the latch with a slot 21, through which the arm 18 may pass during its rotation with the base element 16. This slot 21, intermediate of its ends, is arcuate or bowed away from the door, so that as the arm 18 passes through the intermediate portion of the slot, it will be cammed rearwardly of the oven by the convexity of the slot walls, to draw the door tightly closed and hold it in that condition. The arm 18 may be made of somewhat resilient material, such as sheet metal, so that it will resiliently hold the door tightly closed whenever it is in the intermediate portion of the slot 21.

The bottom walls of the inner and outer shells are provided with substantially aligned apertures 22 and 23 respectively, the aperture 22 of the inner shell being preferably slightly larger than the aperture 23. A strip 24 of sheet metal is formed into a tubular member corresponding somewhat in shape and size to the apertures, and is disposed in the space between the bottom walls of the shells. This tubular member is provided with an inwardly directed flange 25 at its lower end and an outwardly directed flange 26 at its upper end. The inner margin of the flange 25 at the lower end is secured to the bottom wall by flanging the portion of the bottom wall bordering the aperture 23 inwardly and backwardly upon the flange 25, as at 27, which forms a seamed connection between the tubular member 24 and the bottom wall.

The flange 26 at the upper end of the tubular member 24 is seamed to the portion of the bottom wall of the inner shell bordering the aperture, as at 28, so as to form a tight connection between them. The member 24 therefore forms a passage through the two bottom walls of the inner and outer shells, and prevents communication

between the passage through the bottom walls and the space between the bottom walls outside of the apertures. The seamed connection between the two bottom walls and the tubular member provides a very durable structure which imparts considerable rigidity to the two shells.

L-shaped angle strips 29 are secured along the side and rear lateral walls of the inner shell slightly above the bottom wall thereof, upon which strips a heat spreader 30 may be slidingly suspended across the passage through the bottom wall. The heat spreader may be of any suitable construction but, as illustrated, has a depressed portion which is in substantially the plane of the aperture 22 of the bottom wall of the inner shell and this depressed portion may be formed of two sheet metal walls with an interposed layer of insulating material, such as asbestos. The forward edge of the spreader is flanged downwardly, as at 31, so as to rest upon the bottom wall at the forward end of the oven. This flange 31 not only serves to support the spreader at the forward end of the oven, but also prevents passage of the hot gases against the door at the forward end.

The spreader is provided with a plurality of apertures 32 along its two side walls and in proximity thereto, as shown in Fig. 3, so that the heated gases from a burner over which the oven is placed, which pass upwardly through the passage defined by the tubular member, will be deflected by the heat spreader to the two sides of the oven, which may be the two long side walls when the oven has a greater length than breadth. Through these apertures 32, the hot gases pass upwardly into the interior of the inner shell constituting the baking chamber, and then rise to the top of the chamber. The two long side walls of the inner shell are provided, adjacent the top, with a plurality of apertures 33 spaced along the same from front to rear through which the heated gases may pass from the baking chamber to the space between the inner and outer shells at the top.

The outer shell is provided in the long side walls with a plurality of apertures 34 spaced apart lengthwise of the oven and permitting passage of the heated gases from the space between the shells into the atmosphere at the lower part of the oven. The outer shell may be provided upon its inner face with a lining 35 of insulating material, such as sheet asbestos fabric which extends along the tubular part from the top down each side slightly for a short distance, or for its full length, so as to confine the heat in the space between the shells against radiation upwardly or outwardly.

The two side walls of the outer shell may be depressed inwardly to form two cavities

36, one at each side, in which suitable handles 37 may be mounted in such a manner that in their normal positions they will be countersunk within the outer limits of the oven. Thus, the handles will not project outwardly and form troublesome projections in the packing and shipping of the oven. The two handles are, therefore, protected from injury during packing and shipping.

10 The handles preferably comprise bails which are hinged at their upper ends to the side walls of the outer shell and normally descend by gravity into concealed positions within the cavities 36. Each handle may 13 have a hand grip 38 of insulating material or be otherwise constructed to remain cold during use of the oven, so that the oven may be carried about or moved while hot.

A plurality of grate supports 39 (Figs. 2, 3 and 8) are provided upon the side and rear end walls of the inner shell at different elevations or levels, so as to support grates interchangeably at different elevations in the baking chamber. These grate supports are 25 preferably each formed of a metal channel strip which is bent to extend along the side and rear wall of the inner shell with the channel facing inwardly, that is, into the interior of the chamber. The channel stretches, 30 therefore, serve as guideways in which the grate may slide and be supported.

The improved grate comprises a closed frame 40 formed of a metal channel strip which has been bent to conform to the cross sectional shape and size of the interior of the baking chamber of the oven, with the channel facing outwardly or sidewise of the frame. The width of this channel strip is less than the distance between the side arms 40 of the channels forming the grate supports, so that the channel frame 40 may slide within the guideways of the channels 39 serving as the grate supports.

The opposite side walls of the grate frame are provided with apertures 41 in the bottom walls of the channel strip forming the frame (see Fig. 8), and grate bars 42 extend between the apertured stretches of the channel frame and terminate at their ends in tongues 43 of reduced cross section which enter the apertures 41, with the shoulders between the tongues and the body of each bar abutting against the inner face of the frame 40. The ends of the tongues which project into the channels of grooves of the grate frame may be bent over, riveted, or upset so as to firmly interlock the grate bars 42 against withdrawal, and prevent springing apart of the side stretches of the grate frame.

60 In the use of the oven, it may be lifted by the handles 37 and placed over one or more burners, and the hot gases from the burners will pass upwardly through the passage formed in the bottom walls by the tubular member 34. Each spreader 30 will direct

the hot gases to the sides of the oven where they will pass upwardly through the apertures 32 of the spreader into the baking chamber. The gases will then rise through the chamber and pass out therefrom through 70 the apertures 33 into the spaces between the inner and outer shells. The gases will then pass downwardly through the space between the inner and outer shells at the sides of the baking chamber, and leave the oven through 75 the apertures 34 in the lower part of the sides of the outer shell. The hot gases in passing down the side walls in the space between the two shells, will prevent radiation of heat outwardly from the baking chamber through 80 the side walls, and will also prevent chilling of the chamber at the side walls.

The lining 35 of insulating material will prevent too great a heat radiation from the oven on the top, and, if extended down the sides, will also assist in preventing outward radiation of the heat from the sides of the oven. The grates may be placed at different heights by sliding them into the different channel guides and supports 39. The articles to be baked are placed upon the grates, and when the door is closed, it may be locked by turning the base element 16 of the latch to interlock the arm 18 in the slot 21. This resiliently holds the door firmly closed and 95 also assists in holding the latch against turning into unlocked position.

It will be observed that the oven is made practically entirely of sheet metal, with the parts connected by sheet metal seams provided in such positions that they may be formed largely by machine operations instead of hand work. The oven is also surrounded on all sides either by dead air or by hot gases, so that radiation from the baking 100 chamber will be reduced to a minimum in a simple manner. It will be also observed that with this particular construction of the oven, notwithstanding the fact that it is made largely of sheet metal, it will have exceptional 105 rigidity, strength and great durability. It may also have many rounded corners in the baking chamber to facilitate cleaning.

It will be understood that various changes in the details, which have been herein described and illustrated in order to explain the nature of the invention, may be made by those skilled in the art within the principle and scope of the invention, as expressed in the appended claims.

I claim:

1. In an oven, an outer sheet metal shell, an inner sheet metal shell spaced from the outer shell, both of said shells having substantially aligned apertures in the bottom 125 walls, a strip of sheet metal seamed at both edges to the bottom walls of the inner and outer shells respectively and surrounding the apertures thereof, a heat spreader suspended across the passage defined by said strip, said 130

- spreader having passages from face to face along its margin whereby heat deflected by said spreader may enter the inner shell at the margins of the spreader, said inner shell having openings therethrough near the top thereof to permit passage of heat from the inner shell to the space between said shells, said outer shell having openings therethrough adjacent its bottom for the escape of heat from the space between said shells.
10. 2. In an oven, inner and outer sheet metal shells, having aligned lateral door openings and their walls spaced apart, the bottom walls having substantially aligned apertures through which heat may enter the inner shell, a tubular member connecting the apertures to define a passage through said shells for the entrance of hot gases, the inner shell having openings therethrough near the top thereof to permit passage of heat from the inner shell to the space between said shells, said outer shell having openings therethrough adjacent its bottom for the escape of heat from the space between said shells.
15. 3. In an oven, inner and outer sheet metal shells having aligned lateral door openings and their walls spaced apart, the bottom walls having substantially aligned apertures through which hot gases may enter the inner shell, a tubular member connecting the apertures to define a passage through said shells for the entrance of hot gases, the inner shell having openings therethrough near the top thereof to permit passage of heat from the inner shell to the space between said shells, said outer shell having openings therethrough adjacent its bottom for the escape of heat from the space between said shells.
20. 4. In an oven, inner and outer sheet metal shells having aligned lateral door openings and their walls spaced apart, the bottom walls having substantially aligned apertures through which hot gases may enter the inner shell, a tubular member connecting the apertures to define a passage through said shells for the entrance of hot gases, the inner shell having openings therethrough near the top thereof to permit passage of heat from the inner shell to the space between said shells, said outer shell having openings therethrough adjacent its bottom for the escape of heat from the space between said shells, said shells having substantially the shape of a parallelopiped with the openings through the walls thereof for the passage of heat provided in the longer lateral walls.
25. 5. In an oven, inner and outer shells having aligned lateral door openings and their walls spaced apart, the bottom walls having substantially aligned apertures through which hot gases may enter the inner shell, a tubular member connecting the bottom walls at the apertures to define a passage through said shells for the entrance of the hot gases, the shells having the form of a parallelopiped with the door openings at one end, the inner shell having apertures in its longer walls adjacent the top thereof for the passage of the hot gases from the inner shell into the space between the shells, the outer shell having apertures in the longer side walls adjacent the bottom thereof for the discharge of the hot gases from the space between the shells.
30. 6. In an oven, an outer sheet metal shell, an inner sheet metal shell spaced from the outer shell, both of said shells having substantially aligned apertures in the bottom walls, a tubular member connecting the apertures to define a passage through the bottom walls of said shells, the tubular member having its lower edge flanged inwardly and its upper edge flanged outwardly, the bottom wall of the outer shell having the marginal portions bordering the aperture flanged backwardly upon the lower flanged edge, the portion of the bottom wall of the inner shell bordering the aperture, and the adjacent outer flange of the upper end of the tubular member being seamed together.
35. 7. In an oven, a tubular open ended sheet metal shell, an end wall of sheet metal seamed at its edges to one end of the tubular shell and being bent to form a shoulder extending parallel to and spaced from a margin thereof, a second tubular shell disposed in the first shell and spaced therefrom, one end of the inner shell being held in spaced relation to the side walls of the outer shell by fitting against the side marginal shoulder of the end wall of the outer shell, the end wall of the inner shell which abuts the closed end of the outer shell being spaced slightly from said closed end, a frame-like wall seamed to the two outer ends of the inner and outer shells for closing the space between them, a door hinged to the frame-like end wall for movement toward and from a position in which it encloses the opening of the inner shell, said inner and outer shell having apertures in their bottom walls through which heated gases may enter the inner shell.
40. 8. In an oven, an outer sheet metal shell, an inner sheet metal shell, a door supported in hinged relation to said shells to close a door opening thereof, a member rotatably carried by and extending through said door, having an operating element upon its outer end and a locking arm upon its inner end, said inner shell having a slot into which the

locking arm may move during its rotation for locking the door closed, said slot having a portion extending slightly and obliquely toward the rear from the door and beginning approximately at the point where the arm enters the slot, whereby as the arm moves along the slot it will draw the door tightly closed by the camming action between said slot and arm.

10. 9. In an oven, an outer sheet metal shell, an inner sheet metal shell, a door supported in hinged relation to said shell to close a door opening thereof, a member rotatably carried by and extending through said door, having an operating element upon its outer end and a locking arm upon its inner end, said inner shell having a slot into and through which the arm may move during its rotation and with which the arm may cooperate to lock the door closed, said slot having the portion intermediate its ends further from the door opening than its ends whereby as the arm enters the slot and passes along the same from either direction, the camming action between the slot and arm will draw the door tightly closed.

20. 10. In an oven, a grate comprising a channel strip bent into a closed form or frame corresponding to the cross sectional shape of the baking chamber of the oven, with the channel outermost, and cross bars extending between and interlocking with opposite sides of the channel frame to form intermediate

supporting bars therefor, and supporting slides for said grates provided upon the lateral walls of the oven chamber.

11. In an oven, a casing having a baking chamber with grate supporting strips along its lateral walls, a closed grate frame slidably supported upon said strips and being channel shaped in cross section, with the channel facing outwardly of the frame and the bottom wall of the channel forming the inner face of the margin, the bottom wall of the channel at opposite sides of the frame having apertures, and bars extending between such opposite walls and having tongues entering said apertures for support, the entering ends of said tongues being riveted over to prevent their removal.

12. In an oven, a casing having a baking chamber with grate supporting strips along its lateral walls, a closed grate frame slidably supported upon said strips and being channel shaped in cross section, with the channel facing outwardly of the frame and the bottom wall of the channel forming the inner face of the margin, the bottom wall of the channel at opposite sides of the frame having apertures, and bars extending between such opposite walls and having tongues entering said apertures.

In witness whereof, I hereunto subscribe my signature.

LEWIS T. WILCOX.
